(57) **CLAIM**

The ornamental design for a mailbox tray, as shown and described.

DESCRIPTION

FIG. 1 is a perspective view of a first embodiment of the mailbox tray.

FIG. 2 is a top view of a first embodiment of the mailbox tray.

FIG. 3 is a bottom view of a first embodiment of the mailbox tray.

FIG. 4 is a left side view of a first embodiment of the mailbox tray.

FIG. 5 is a rear side view of a first embodiment of the mailbox tray.

FIG. 6 is a front view of a first embodiment of the mailbox tray.

FIG. 7 is a back view of a first embodiment of the mailbox tray.

FIG. 8 is a perspective view of a second embodiment of the mailbox tray.

FIG. 9 is a top view of a second embodiment of the mailbox tray.

FIG. 10 is a bottom view of a second embodiment of the mailbox tray.

FIG. 11 is a left side view of a second embodiment of the mailbox tray.

FIG. 12 is a rear side view of a second embodiment of the mailbox tray.

FIG. 13 is a front view of a second embodiment of the mailbox tray.

FIG. 14 is a back view of a second embodiment of the mailbox tray.

FIG. 15 is a perspective view of a third embodiment of the mailbox tray.

FIG. 16 is a top view of a third embodiment of the mailbox tray.

FIG. 17 is a bottom view of a third embodiment of the mailbox tray.

FIG. 18 is a left side view of a third embodiment of the mailbox tray.

FIG. 19 is a rear side view of a third embodiment of the mailbox tray.

FIG. 20 is a front view of a third embodiment of the mailbox tray; and,

FIG. 21 is a back view of a third embodiment of the mailbox tray.
